[57] CLAIM

The ornamental design for a shoe midsole, as shown and described.

DESCRIPTION

FIG. 1 is a right elevational view of a shoe midsole showing our new design;

FIG. 2 is a left side elevational view thereof;

FIG. 3 is a front elevational view thereof;

FIG. 4 is a rear elevational view thereof;

FIG. 5 is a cross section taken along the line 5—5 of FIG. 2;

FIG. 6 is a cross section taken along the line 6—6 of FIG. 2; and,

FIG. 7 is a cross-sectional view taken along the line 7—7 of FIG. 2.

The broken line showing of a shoe upper in FIGS. 1-4 and a shoe sole in FIGS. 1-6 is for illustrative purposes only and forms no part of the claimed design.

FIG. 4**FIG. 3**FIG. 6

FIG. 5
